UNITED STATES PATENT OFFICE.

CARL J. MELLIN, OF SCHENECTADY, NEW YORK.

STEAM-PIPE FOR ARTICULATED LOCOMOTIVES.

1,020,435.

Specification of Letters Patent. Patented Mar. 19, 1912.

Application filed January 2, 1912. Serial No. 669,017.

To all whom it may concern:

Be it known that I, CARL J. MELLIN, of Schenectady, in the county of Schenectady and State of New York, have invented a certain new and useful Improvement in Steam-Pipes for Articulated Locomotives, of which improvement the following is a specification.

My invention relates to locomotives of the articulated or Mallet type, more particularly those that are equipped with superheaters, and its object is to provide means for delivery of steam to the high pressure cylinders of locomotives of such type, whereby the use of the "belt pipe" and the resultant obstruction to the view of the engineer will be avoided, and in the case of superheater engines, connection may be made with the superheater as directly as possible.

The improvement claimed is hereinafter fully set forth.

In the accompanying drawings: Figure 1 is a diagrammatic side view of an articulated compound locomotive, illustrating an application of my invention; Fig. 2, a side view, partly in section, and on an enlarged scale, of a portion of the same, and, Fig. 3, a transverse section through the smoke box.

My invention is herein exemplified as applied in a locomotive engine of the Mallet articulated compound type, comprising a rear frame, 8, supported on a plurality of driving wheels, 1, and a front frame, 8^a, supported on a plurality of driving wheels, 1^a. The rear frame, as in the regular practice in locomotives of this type, carries at its front end, which is located nearly at the middle of the length of the boiler, a pair of high pressure cylinders, 12^a, the pistons of which are coupled to crank pins on the driving wheels, 1, and the front frame carries a pair of low pressure cylinders, 12^b, the pistons of which are coupled to crank pins on the driving wheels, 1^a. The boiler, 4, is fixed to the rear frame, 8, and the front and rear frames are coupled, in the longitudinal central plane of the locomotive, by a pivot pin, 8^b, the forward portion of the boiler being thus, as is characteristic in locomotives of this type, free to swing or traverse laterally, relatively to the front frame, 8^a, in passing curves.

In the practice of my invention, the valve chests, 12^b, of the high pressure cylinders, 12^a, are connected with the main steam sup-

ply pipe, 61, which leads from a throttle valve chamber, 42, located in the dome, 41, of the boiler, either directly in ordinary saturated steam locomotives, or through the 60 intermediation of a superheater, 70, when a device of that class is applied, by branch steam pipes, 63, located within the smoke box, 4^a, and lateral steam pipes, 65, connected, at their forward ends, to the lower 65 ends of the branch steam pipes, 63, and extending rearwardly, below the shell of the boiler, 4, to the valve chests, 12^b, of the high pressure cylinders, 12^a.

In order to protect the lateral steam pipes, 70 65, from the cooling action of the atmosphere, they are incased in lagging, 65^a, of any suitable and preferred material, and ball joint rings, 65^b, are fitted between the 75 ends of said pipes and the valve chest nozzles or flanged openings to which they are connected. Expansion and contraction of the pipes, 65, are compensated by slip or expansion joints, 65^c, which are, preferably as shown, located adjacent to the high pressure valve chests.

It will be seen that by the above construction, the usual belt pipes are dispensed with, and connections effected with a superheater or with the front T head of the main supply pipe as directly as is practicable. The lateral steam pipes, 65, beneath and close to the boiler shell, do not obstruct the view of the engineer, nor offer any obstruction to the reverse gear of the forward cylinders or any other moving members of the locomotive.

I claim as my invention, and desire to secure by Letters Patent:

1. In an articulated locomotive, the combination of a boiler, cylinders fixed relatively to the boiler, in rear of the smoke box thereof, a main steam supply pipe within the boiler, branch steam pipes communicating therewith, and extending downwardly in the smoke box of the boiler, and lateral steam pipes extending rearwardly adjacent to the boiler shell from the branch steam pipes to the cylinders.

2. In an articulated locomotive, the combination of a boiler, cylinders fixed relatively to the boiler, in rear of the smoke box thereof, a main steam supply pipe within the boiler, branch steam pipes communicating therewith and extending downwardly in the smoke box of the boiler, lateral steam pipes extending rearwardly adjacent to the

boiler shell from the branch pipes to the cylinders, and expansion joints in said lateral steam pipes.

3. In an articulated locomotive, the combination of a boiler, cylinders fixed relatively to the boiler, in rear of the smoke box thereof, a main steam supply pipe within the boiler, a superheater connected thereto, branch steam pipes communicating with

said superheater and extending downwardly in the smoke box of the boiler, and lateral steam pipes extending rearwardly adjacent to the boiler shell from the branch steam pipes to the cylinders.

CARL J. MELLIN.
